UNITED STATES PATENT OFFICE.

ROBERT E. WALLISER, OF CHICAGO, ILLINOIS.

FRINGE-TASSELING MACHINE.

Application filed February 9, 1926. Serial No. 87,038.

My invention relates to a fringe tasseling machine, designed for use in producing tassels on fringe heading material, borders or trimmings for upholstery, cushions, curtains, and the like, and for use as well in such other places or capacities where it can be conveniently or advantageously employed in adorning finishing materials with tassels, and the main object of my invention is the provision of an automatic machine of this character which will embody certain desired features of simplicity, efficiency, and convenience, and which will be capable of producing an attractive tassel fringe at a low cost.

It is within the province of the present invention to provide a machine of this class characterized by having means for holding or positioning the fringe heading to be furnished with the tassels; by having means for applying the tassel material in the form of warp rope to the fringe heading; by having means for securely holding the warp rope during the severing of the tassel lengths therefrom and during the interlocking of the severed lengths with the fringe heading; by having means for severing the tassel lengths; by having means for interlocking the tassel lengths with the fringe heading; and for combing out the tassel lengths; by having means for compressing the tassel lengths prior to binding the same into tassels; by having means for forming wire binders and binding the tassel lengths into tassels upon the heading material, and finally by having means for trimming the completed tassels.

Other objects will appear hereinafter.

The invention consists in the combinations and arrangements of parts hereinafter described and claimed.

The invention will be best understood by reference to the accompanying drawings forming a part of this specification, and in which,

Fig. 1 represents a front elevational view of my machine, parts being broken away and parts being shown in section;

Fig. 2 represents a top plan view of my machine;

Fig. 3 represents a horizontal cross section taken substantially on the line 3—3 of

Fig. 1, this view showing the operating shaft and parts associated therewith;

Fig. 4 represents a vertical cross section taken substantially on the line 4—4 of Fig. 1 and showing the operating treadle, the cam controlled mechanism for operating the wire binding mechanism and the compressor fingers;

Fig. 5 represents a vertical cross sectional view taken substantially on the line 5—5 of Fig. 1, showing the cam controlled mechanism for operating the holding jaws and also for operating the folding and combing fingers;

Fig. 6 represents a vertical cross section taken substantially on the line 6—6 of Fig. 1, showing the cam controlled mechanism for operating the claw, and showing also the folding and combing fingers in elevation;

Fig. 7 represents a vertical cross section taken substantially on the line 7—7 of Fig. 1, showing the cam controlled mechanism for operating the loop positioning collar, also showing the cam controlled mechanism for operating the trimmers, this view further showing in broken lines the cams controlling the operation of the claw and sleeve;

Fig. 8 represents a vertical cross section taken substantially on the line 8—8 of Fig. 1 and showing the cam controlled mechanism for operating the cutters for shearing the tassels from the warp rope;

Fig. 9 represents a vertical cross section taken substantially on the line 9—9 of Fig. 1, this view showing the cam controlled mechanism for operating the sleeve shaft;

Fig. 10 is a top plan view taken on the line 10—10 of Fig. 5 and illustrating the top clamp for the binding wire;

Fig. 11 is a side elevation showing the mechanism for feeding the binding wire;

Fig. 12 is a top plan view, partly in section, of the parts shown in Fig. 11;

Fig. 13 is a top plan view showing a tassel as it appears when formed and bound upon a heading loop, and also showing the means for combing the tassel and the means for trimming the same;

Fig. 14 is an elevational view from the front or operator's side of the machine, this

view being taken substantially on the line 14—14 of Fig. 2, and this view showing the wire binding mechanism, the folding and combing fingers and the trimmers, parts being illustrated in section;

Fig. 15 is a top plan section taken substantially on the line 15—15 of Fig. 14 and showing the wire cutting and binding mechanism;

Fig. 16 is a sectional elevation taken substantially on the line 16—16 of Fig. 2, looking from the inside of the machine toward the front thereof and showing the female stapling die member, the compressor fingers and the cutters for severing the tassel lengths;

Fig. 17 is a view similar to Fig. 16 but showing the male stapling die member carrying the staple or wire binder of the tassel length in position to surround the tassel length therewith, and also showing the compressor fingers squeezing the tassel;

Figs. 18 to 21, inclusive, are vertical sectional detail views showing the successive steps involved in carrying the warp rope through the loop heading;

Fig. 22 is a top plan section taken substantially on the line 22—22 of Fig. 21 and showing in particular the holding jaws closed upon the warp rope;

Fig. 23 is a vertical cross section illustrating the tassel length after it has been cut off the warp rope with the folding and combing fingers folding the tassel length upon the heading loop;

Fig. 24 is a vertical cross section illustrating the folding fingers as they appear when combing out the tassel length upon the heading loop prior to the application of the binding wire; and

Fig. 25 is a top plan showing the collar for holding the heading loops on which the tassels are produced, showing the means for supporting the collar, and also showing the holding jaws for the tassel lengths along with the means for closing said jaws.

As illustrated in the accompanying drawings, my fringe tasseling machine preferably embodies a table 30 suitably supported upon end standards 31, and a housing 32 arranged upon the table along the front portion thereof to afford a shield for protecting the operator of the machine from coming into contact with the various operating mechanisms and further to afford a support upon which the operator may suitably rest her arms while performing her work. In the housing or shield 32 is a slot 33 in which operates a collar 34 which has an open side 35. As illustrated in Figs. 2 and 25, the collar 34 is carried by a head 36 secured by screw elements 37 to an arm 38 which is pivoted at 39 for movement between the two stops 38' upon the table 30 within the shield or housing 32. The head 36 has its under face recessed

at 40 for the operation of a pair of holding jaws 41 which are pivoted intermediate their length at 42 to said head 36. At their rear ends, these holding jaws are made with complementary hook-like ends 43 adapted to receive and hold the tassel material therebetween. These holding jaws are normally held in open position by means of spring members 44 which are arranged to bear upon the correspondingly curved and cam like outer ends 45.

The arm 38, pivoted at 39 upon the table and within the shield or arm rest 32 and carrying the open collar 34 and also the pivoted holding jaws 41, is operated by means of a chain of members comprising a pivoted link 46, with which is engaged at 47 a universal joint 48, and a depending arm 49 (Fig. 7) fulcrumed at 50 to a depending bracket 51 having adjustment in the table slot 52 and having support from a plate 53 adjustable upon the table by means of a clamping device 54. Under this arrangement, the bracket 51 to which the arm 49 is fulcrumed, is adjustably supported from the table. The lower end of the arm 49 carries a roller 55 arranged to turn on the ring cam 56 supported upon lugs 57 cast on the disc 58 fixed upon a shaft 59 which represents the main driving shaft of the machine. The ring cam 56 is adjustable upon the lugs 57, the means for this purpose comprising pins 60 which pass through elongated slots 61 in the ring cam.

By referring to Figs. 1, 2 and 4, it will be seen that the main driving shaft 59 is arranged to be driven by a pulley 62 through a belt 63 which may receive its power from any suitable source. The pulley 62, normally loose upon the shaft 59 and provided with projecting pins 62', is arranged to cooperate with a spring pressed clutch composed of two disk parts 64 and 64' keyed on the shaft and connected by a spacing pin 222. The disk part 64 is provided with openings 223 for receiving the pins 62' and with a contact pin 223'; while the connected disk part 64' has a cam 224 and a shield 225, both of which project toward the disk part 64. 65 is a shifting lever made with a cam edge 226 and a stop lug 227; said shifting lever being pivoted at its lower end on a stud 228 where it is provided with oppositely directed arms 229 and 230. A link 66 operatively connects the arm 229 with a treadle member 67. A repositioning spring 231, connected with the other arm 230, as best shown in Fig. 4, normally urges the shifting lever into such position that its cam edge 226 will engage the cam 224 for shifting the clutch against the urge of spring 232 to free the disk part 64 from the pins 62', and also at the same time that its stop lug 227 will be in the path of the contact pin 223' to prevent turning of the shaft 59. With the depression of the

treadle member 67, the shifting lever 65 is pivoted away from the clutch, withdrawing the cam edge 226 from cam 224 and stop lug 227 from contact pin 223' thereby freeing the clutch for operative connection with the pulley 62', and it is also such that the clutch will be automatically thrown out after each revolution of the main driving shaft 59. Therefore, to operate the machine, it is only necessary to depress the treadle 67 each time the main shaft is to make a revolution. Adverting to Fig. 7, it will be seen that cam ring 56 comprises an open ring having a cam extremity 68, a periphery 69 and a cam extremity 70 for engagement by the roller 55 on the fulcrumed arm 49 suitably tensioned by a pull spring 49'. By making the cam ring in this manner, each time the main driving shaft 59 rotates the cam extremity 68 engages the roller 55 so as to move the collar 34 to the rear of the slot 33, which, it will be observed, is an open slot; and each time the cam extremity 70 is disengaged from the roller 55, the collar will be moved to the front end of the slot 33, owing to the tension of the pull spring 49'.

As best illustrated in Figs. 18 to 21, the collar 34 protrudes a distance above the arm rest 32; and as best illustrated in Fig. 13, the collar is designed to serve as a suitable holder for the loops formed on the fringe heading 71. In accordance with the principles involved in this machine, each time the collar is moved to the front end of the slot 33, the operator of the machine may place thereon one of the heading loops 72 on which a tassel is to be formed and bound; and each time the collar moves rearwardly of the slot a tassel is formed and bound on the heading loop, which is removed from the collar on the ensuing forward movement thereof and just prior to the application of a new heading loop. From this, it will be understood, that the operator of the machine will be required to remove a tasseled heading loop 72 and to apply an untasseled heading loop 72 during each forward reciprocation of the collar, which, of course, means that these operations must be carried on during the interval of time that lapses between the disengagement of the roller 55 with the terminal cam 70 and the engagement thereof with the terminal cam 68.

The tassel lengths 73, from which the tassels are produced, are cut from warp rope 74 fed through a tube 75 from any suitable source of supply where the warp rope may be suitably held under tension, as by a wheel, bobbin or the like. The feed tube 75 is preferably supported in such position that the collar 34 will be in substantial alinement therewith when it is moved into its rearward position, so that the warp rope may conveniently be seized at the end of the feed tube 75 and drawn through the collar 34. The

means for drawing or pulling the warp rope through the collar 34 comprises a sleeve 76 movable on a rod 77 which is hollowed and split at its upper end so as to produce the spring claws 78. The sleeve 76 is operatively held by a guide block 78' which is suitably attached to the table 30. To the lower end of the sleeve 76 is attached an offset head 79 attached to a rod 80 provided with a yoke 81 arranged to operate on the main shaft 59 (Fig. 9). Said yoke 81 is operatively positioned at its lower end by means of a rod 82 which slides in a guide 83 attached to the main frame. The yoke 81 carries a roller 84 which turns in a cam groove 85 cut in the face of the disc 58. Turning now to Fig. 6, it will be seen that the claw rod 77 also has a yoke 86 with a rod 87 operating in the guide 83. Yoke 86 carries a roller 88 which turns in cam groove 89 cut in the face of disc 90 which is pinned fast to the main shaft 59. The claw rod and sleeve therefore are arranged to be reciprocated through the collar 34 when the same is positioned to receive the warp rope therethrough; and the purpose of the claw and sleeve arrangement is to provide means for pulling the warp rope through the collar sustained heading loop for the production of the tassel thereon. The cams controlling the claw rod and sleeve are so constructed and arranged that the claws 78 will be locked in closed position when passing through the collar; and the construction and arrangement of said cams are further such that above the collar where the warp rope is seized by the claws, the claw rod will be given an advancing movement by the cam high point 92 to unlock the claws from the sleeve, the sleeve for this action being slowed up because of the groove section 91 and subsequently being advanced to lock the claws upon the seized warp rope by reason of the cam groove section 93. Below the collar, where the warp rope is to be released, the claw rod is given an advancing movement to unlock the claws from the sleeve by reason of the cam groove section 89 on the disc 90; and after the releasing of the warp rope and before reaching the collar, the sleeve is given an advancing movement to again lock the claws by reason of a cam groove section 93' on disc 58. In this connection it is to be noted that the cams for the claw and sleeve arrangement are so related to the cam for moving the collar that the claw and sleeve will be projected through the collar immediately the collar is moved into position to receive the warp rope. Immediately upon the warp rope being drawn by the claw and sleeve arrangement through the collar, the holding jaws 41 are closed upon the warp rope just below the collar. The means for closing the holding jaws against the tension of the springs 44 comprises a rock shaft 94 preferably held by

bracket bearing 95 (Fig. 25) and carrying a shoe 96 arranged to be swung into the path of the parts 45 so as to force the jaws 41 to close with the opposite extremities 43 firmly 5 clamping the warp rope. Rock shaft 94 is turned to effect the closing of the jaws against the tension of a return spring 94'. The rock shaft 94 is operated by means of crank 97, and pivotally connected arms 98 10 and 99 (Fig. 5), the last named arm having pivoted action at one end upon a fixed shaft 100. The arm 99 carries a roller 101 arranged in the path of a cam 102 fixed on the main shaft 59. By this arrangement, the 15 shoe 96 is swung into position to close the jaws upon the warp rope just as soon as the same has been pulled through the collar sustained heading loop.

Following upon the clamping of the warp 20 rope by the holding jaws, the warp rope is severed to produce the tassel length 73. This operation is accomplished by means of plate cutters 103 and 104 arranged to slide in housing 105 supported upon uprights 106 25 rising from the table 30. The cutters 103 and 104 have apertures 103' and 104', respectively, for the reception therethrough of the warp rope; and the walls defining said apertures are ground to form cooperating 30 cutting edges. To effect the severing of the warp rope, the cutters 103 and 104 are operated in opposite directions, the power for operating the same being obtained from a rock shaft 110 arranged in bearings 111 supported upon the table 30. Carried by said 35 shaft 110 is a cross arm 109 to the free ends of which are pivoted links 108, of which one is pivoted to a lug 107 on the cutter 103, while the other is similarly connected to a 40 similar lug on the cutter 104. The shaft 110 has an arm 112 to which the upper end of a depending link 113 is pivoted. Said link 113 is preferably made adjustable so as to vary the stroke of the cutters at will. The 45 lower end of link 113 is pivoted to a crank arm 114 which has rocking movement on the fixed shaft 100. To the free end of the arm 114 is fixed a roller 115 arranged to ride on the periphery of cam 116 on the main 50 operating shaft 59. This arrangement for severing the warp rope is so correlated to the application of the holding jaws that the severing of the warp rope takes place immediately upon the closing of the holding 55 jaws upon the tassel length to be cut off. With the arm 114 (Fig. 8) is associated a repositioning spring 117.

Having thus sheared off the tassel length, the next step is to fold the same while it is 60 being held by the holding jaws upon the heading loop surrounding the collar. To this end, I provide a pair of folding and 65 combing fingers 118 (best seen in Fig. 24 and Figs. 18 to 21). Fingers 118 are formed 70 at corresponding ends with hook-like por-

tions 118' having half round faces 118" 75 jointly comprising means for surrounding and combing the tassel length. As best shown in Fig. 24, the fingers 118 are pivoted intermediate their length upon a heading 80 shaft 119 fixed to a shaft 120 keyed for reciprocating movement in a bearing head 121 constituting part of a bracket 122 rising from the table 30. Above the table 30, the shaft 120 has a crank (Fig. 2) 123 connected to a link 124 for connection through a suitable crank 125 with a rock shaft 126 journaled in uprights 126' upon the table 30. To the rock shaft 126 is pinned a crank 127 on which is 85 adjustable an arm 128 having pivoted connection with rock arm 129 operatively attached at one end to the shaft 100 (see Fig. 5). Rock arm 129 carries a roller 130 arranged to turn on cam 102. By this arrangement, the shaft 120 carrying the folding and combing fingers 118, is reciprocated in the bearing head 121; it being noted in this connection that a pull spring 131 (Fig. 5) suitably tensions the rock arm 129. The bearing head 121 has a top notch 133 forming a cam surface for the curved shoulder 132 of the top arm 118, while at the bottom of the bearing head 121 there is provided a shoe 134 for engaging the curved shoulder 132 of the bottom finger 118. Beyond the 90 bearing head 121, the free ends of the fingers 118 are connected by a pull spring 135, whereby normally to urge the fingers into open position and whereby to maintain the curved shoulders 132 of the fingers in sliding contact with the bearing parts 133 and 134 so that during the advancement of the shaft 120 the fingers will be opened by the spring 135 and further so that upon the 95 retraction of said shaft 120 the fingers will 100 be closed. The shaft 120 is thus arranged for reciprocating movement and the fingers 118 are thus pivoted on said shaft for opening and closing movement; it being noted in this connection that the shaft is so positioned as to operate in line with the open side 35 of the collar 34 and further that when the shaft is advanced toward the collar the fingers 118 will be opened to lie upon 105 opposite sides of the collar in position to 110 have the hooked ends 118' thereof engage the portions of the tassel length extending above and below the collar in such manner as to fold said portions upon themselves 115 during the retracting movement of the shaft 120, the half round portions 118" combing the folded-over portions between them until as best illustrated in Fig. 24, the folded-over 120 portions are united as a tassel upon that portion of the heading loop which crosses 125 the open side 35 of the collar 34. Under this arrangement, the fingers 118 are advanced to engage the severed tassel length both above and below the collar and to comb the severed length into folded position upon 130

the heading loop. After the combing and folding operation has been completed, the severed tassel length, now comprising a tassel, is compressed, bound by a wire staple, and trimmed. Referring to Fig. 5, 136 designates an upright bracket having feet 137 mounted on the table 30. In this bracket is provided a lengthwise slot 138 (Fig. 15) which is closed by a side plate 139 slotted 140 at 140. Arranged for sliding movement in the slot 138 are two bars 141 and 142 which are operated by cams 143 and 144, respectively, provided on a rock shaft 145 having bearings 146 rising from the table 30. The 15 rock shaft 145 has a crank arm 147 (Fig. 1) linked to arm 148 which is pivotally connected to arm 149 fast on a rock shaft 150 operatively supported by the frame. Said arm 149 has a roller 151 arranged to turn 20 on cam 152 fast on the main shaft 59. By this arrangement the bars 141 and 142 are reciprocated each time the shaft 59 revolves, and a pull spring 153 (Fig. 4) serves as 25 means whereby to maintain the roller 151 in operative relation with the cam 152. The bar 142 is advanced ahead of the bar 141 and has a cutting edge 154 adapted to shear off a length from a wire 155 which is fed 30 downwardly through clamping devices 156 and 157. The clamping device 156 is supported upon rods 158 rising up from the bracket 136 and comprises cooperating clamping members 159 and 160 which are held together by pins 161 and compression 35 springs 162 arranged on the pins and resiliently urging the member 160 into clamping relation with the member 159 (Fig. 10).

The clamping device 157 comprises a carrier or block mounted for reciprocation on the rods 158. This carrier is reciprocated by means of a gripping shoe 163 which works on a pivot stud 163' and is connected by a link 164 to a crank arm 165 fast on rock shaft 166 which is mounted in bearings 167 secured to the table 30. The rock shaft 166 has an arm 168 (see Fig. 2) linked to arm 169 which extends to a crank 170 fast on shaft 110 which is driven from cam 116 on the main shaft 59. By this arrangement the carrier or block 157 is vertically reciprocated by power obtained from the shaft 110. Co-operating with the gripping shoe 163 is a stationary gripping shoe 171. These shoes serve to grip and advance the wire 155 with 55 the downward movement of the block or carrier 157 on which there is a guide lug 172 for the wire. Under this arrangement, each time the carrier block 157 is elevated the gripping shoe 163 is pivoted so as to be 60 drawn out of gripping engagement with the wire 155. As best illustrated in Fig. 12, the carrier or block 157 is frictionally held to one of the rods 158 by means of a shoe 173 which is acted on by a spring 174 and a 65 suitable adjusting screw 175. Under each

downward movement of the carrier or block 157 a length of wire sufficient to extend around and bind a tassel, is fed down through a guide 176 arranged in bracket 136 (Fig. 14); and terminatively with this feeding movement a similar length of wire is severed by the cutting edge 154 of bar 142. The bar 142 is bifurcated to produce a slot 181 in advance of which is an anvil member 177 which projects from an arm 178 pivoted at 179 between two brackets 180. The wire 155, prior to being severed, is fed between the anvil 177 and the furcations of the bar 142. Arranged to operate in the slot 181 is an elongated die member 182 which is formed integral with the bar 141. The free end of the die member 182 is concaved as at 183 for the purpose of bending the cut off wire on the curved anvil 177 so as to produce a U-shaped staple. The bar 141 is made with a cam surface 184 designed to engage a co-operating shoe 185 pinned to the arm 178. This arrangement is such that the anvil 177 will be swung clear of the path of the die member 182 prior to the movement thereof 90 for placing the U-shaped staple on the tassel. The arm 178 is repositioned by a spring 186 after each action.

The U-shaped staple designated by the numeral 188 and produced in part upon the anvil 177 and in part by the die member 182 pressing it into the groove 187 in bar 142, is advanced by the die member into a groove 189 provided in bar 190 (Figs. 16 and 17) which reciprocates in upright posts 106. 100 The said bar 190, which represents a female die, is reciprocated by cam 191 on rock shaft 192 arranged in bearings 193 upon the table 30. Rock shaft 192 has a crank arm 194 linked to arm 195 (Fig. 8) which is pivoted 105 to a crank arm 196 having one end fast on rock shaft 150. As shown in Fig. 22, the groove 189 is turned laterally at 197 so as to slightly twist and over-lap the ends of the U-shaped staple as such ends are closed to 110 complete the wire binding 198 of the tassel (Fig. 13).

Just prior to the application of the U-shaped staple to the tassel by the die member 182, the tassel 73 is compressed to a size 115 to receive the U-shaped staple thereon. As a means for compressing the tassel, the female bar 190 is equipped with an eyelet 199 through which is extended a pair of fingers 200. These fingers occupy a position in a 120 groove 201 in caps 202 attached to posts 106 (Figs. 7 and 16). The forward portions 203 of the fingers are bent in opposite directions so as to be closed upon the tassel 73 by the eyelet 199 when the female bar 125 190 is moved forward. A spring 204 (Figs. 1 and 16) is arranged to hold the bars 141 and 142 in operative relation to their cams 143 and 144; and a spring 205 holds the female bar 190 in operative relation to its 130

cam 191. Under the operation of the binding mechanism, therefore, a wire length is first severed from the feed wire 155, a U-shaped staple is formed, the tassel is compressed to receive the staple, and finally the staple is applied to the compressed tassel and bound thereon.

The means for trimming the wire bound tassel 73 consists of a pair of cooperating snips 206 and 207. The snip 206 is carried by a rock shaft 206' operatively arranged in bearing 208 which is secured to the table 30. The rock shaft 206' has an abutting collar 209 provided with a crank 210 which is connected by a link 211 (Fig. 7) with an arm 212 fulcrumed for rocking movement upon the fixed shaft 100. The fulcrumed arm 212 carries a roller 213 arranged to turn on a cam 214 fast on the main operating shaft 59. Pivoted at 215 to the rear free end of the arm 212 is a connecting link 216 whose top end has pivotal connection with a crank 217 arranged on a rock shaft 218 which extends through the rock shaft 206' and carries the snip 207. A coiled spring 219, surrounding the shaft 218 and imprisoned between collar 209 and a collar 220, serves to urge the rock shaft 218 in a direction to keep the snips 206 and 207 in proper frictional engagement. The snips 206 and 207 are thus arranged for opening and closing movement, to have a scissors-like action for trimming the free ends of the tassel 73 as best illustrated in Fig. 13, it being observed that the tassel is still held by the folding and combing fingers during the trimming operation. For carrying away the waste resulting from the trimming operations, I provide a downwardly and rearwardly inclined chute 221.

As has been previously intimated, the operator may employ the shield 32 which protects her from the working mechanisms as a rest for her arms while applying and removing the heading loops from the collar. In the operation of the machine, the operator having applied a heading loop 72 to the collar, depresses the treadle thereby throwing in the clutch and automatically operating the various mechanisms as hereinbefore described. Upon the application of power to the main driving shaft, the collar is moved rearwardly in its slot to the position for receiving the warp rope which is drawn therethrough by the claw and sleeve mechanism and is thereupon seized by the holding jaws. Thereupon the warp rope is severed and the severed tassel length is combed into folded position upon the collar sustained heading loop. The wire stapling mechanism is then brought into operation with the result that the wire is fed, a length thereof cut off and formed into a U-shaped staple which is applied to the folded tassel as soon as the same is compressed for the

purpose; and finally, the tassel having been bound, the free ends thereof are trimmed before the collar is moved forwardly in its slot for the removal of the heading loop with the tassel applied thereto. These mechanisms are operated during a single revolution of the main driving shaft. Therefore, during each revolution of the main driving shaft a tassel is produced upon a heading loop. 75

While I have illustrated and described the preferred form of construction for carrying my invention into effect, this is capable of variation and modification without departing from the spirit of the invention. I 80 therefore, do not wish to be limited to the precise details of construction set forth, but desire to avail myself of such variations and modifications as come within the scope of the appended claims. 85

Having described my invention what I claim as new and desire to secure by Letters Patent is:

1. A machine of the class described including an open collar for sustaining a heading loop in spread condition with a portion thereof exposed; co-operating mechanical means for automatically passing tassel material through said spread loop; means comprising co-operating fingers arranged to operate upon the tassel material for folding it over upon the exposed portion of said loop; and instrumentality for securing together the folded over portions of the tassel material, substantially as described. 90

2. A machine of the class described including means for holding a heading loop; means for pulling tassel material through said loop; means for holding the applied tassel material in relation to said loop; means arranged to operate upon the tassel material for folding it upon said loop; and instrumentality for wire binding the folded portions into a tassel, substantially as described. 105

3. A machine of the class described including a holder for sustaining a heading loop in spread condition with a portion thereof exposed; means for passing tassel material through the opening of the spread loop; instrumentality comprising cooperating fingers for engaging and folding the tassel material upon the exposed portion of said loop; and cooperating snips for trimming the folded tassel material, substantially as described. 110

4. A machine of the class described including an open collar for holding a heading loop in spread condition with a portion thereof completely accessible; means for passing tassel material through said spread loop; cooperating jaws for holding the applied tassel material in relation to said loop; cooperating fingers for engaging and folding the tassel material over the accessible portion of said loop; and cooperating snips 115

for trimming the folded over tassel material, substantially as described.

5. A machine of the class described including means for holding a heading loop; means for pulling tassel material through said loop; means for folding the tassel material upon said loop to produce a tassel thereon; means for wire binding the tassel; and means for trimming the tassel, substantially 10 as described.

6. A machine of the class described including a holder for supporting a heading loop in spread condition with a portion thereof completely accessible; means for 15 passing tassel material through said spread loop; cooperating jaws for holding the applied tassel material in relation to said loop; cooperating fingers arranged to operate upon the tassel material for engaging and combining it into folded position upon the accessible 20 portion of said loop; mechanism for binding together the folded over portions of the tassel material; and a pair of cooperating snips for trimming the folded over portions, 25 substantially as described.

7. A machine of the class described including means for holding a heading loop; means for drawing tassel material through said loop; means for holding the applied 30 tassel material in relation to said loop; means arranged to operate upon the tassel material for combing it into folded position upon said loop to produce a tassel thereon; instrumentality for wire binding the tassel; and 35 means for trimming the tassel, substantially as described.

8. A machine of the class described including a collar open at one side for holding a heading loop in spread condition and accessible; mechanism for passing tassel material through the spread of said loop; instrumentality comprising cooperative fingers for 40 folding the tassel material through the open side of said collar and upon the accessible portion of said loop; mechanism operative to bind the folded portions of the tassel material; and means associated with the binding mechanism for compressing the folded portions prior to the binding operation, substantially 45 as described.

9. A machine of the class described including a collar open at one side for holding a heading loop in spread condition and accessible; a jaw and sleeve arrangement for 50 passing tassel material through said spread loop; cooperating jaws for holding the applied tassel material in relation to said loop; cooperating fingers arranged to fold the tassel material through the open side of said collar and upon the accessible portion of said loop; and means for securing together the folded over portions of said tassel material, substantially as described.

10. A machine of the class described including means for holding a heading loop;

means for drawing tassel material through said loop; means for folding the tassel material upon said loop to produce a tassel thereon; means for compressing the tassel material to receive a binder; instrumentality for 70 applying a wire binder to the compressed tassel; means for trimming the bound tassel, substantially as described.

11. In a machine of the class described, the combination with collar means for supporting a heading loop in spread condition, there being an opening in the side of said collar means, of means for passing tassel material through said spread loop; means comprising 75 combing fingers for engaging the tassel loop at the opposite ends of said collar means and combing it upon the heading loop portion exposed at the open side of said collar means and snips for trimming the folded over portions, substantially as described.

12. In a machine of the class described, the combination with collar means for supporting a heading loop in spread condition, there being an opening in the side of said collar means; of means for passing tassel 80 material through said spread loop; a pair of jaws arranged to seize and hold the tassel material passed through said spread loop; mechanism operative to sever the length of the tassel material held by said jaws; and 85 combing fingers for engaging the severed length at the opposite ends of said collar means and for folding the same upon the heading loop portion exposed at the open side, substantially as described.

13. In a machine of the class described, the combination with means for feeding tassel material and a movable collar for holding a heading loop in relation thereto, of means arranged to seize the tassel material 90 from said feeding means and to draw it through said loop; means operable between said feeding means and collar for severing a tassel length from said tassel material; means for holding the severed length; and 95 means for interlocking the severed length with said loop to produce a tassel thereon, substantially as described.

14. In a machine of the class described, the combination with means for feeding the 100 tassel material and a movable collar for holding a heading loop in relation thereto, of means arranged to seize the tassel material from said feeding means and to pull it through said loop; means operable between said feeding means and collar for severing a tassel length from said tassel material; 105 cooperating jaws for holding the severed length; and cooperating fingers for interlocking the severed length with said loop, 110 substantially as described.

15. In a machine of the class described, the combination with means for feeding tassel material and a movable collar for holding a heading loop in relation thereto, of 115

- means arranged to seize the tassel material from said feeding means and to draw it through said loop; means operable between said feeding means and collar for severing 5 a tassel length from said tassel material; cooperating jaws for holding the severed length; cooperating fingers for combing the severed length into folded position on said loop; and instrumentality for binding the 10 folded portions of the severed length, substantially as described.
16. In a machine of the class described, the combination with a collar for receiving and holding a heading loop, of means for pulling 15 the tassel material through said loop; cooperating jaws for holding the tassel material in said loop; and cooperating fingers for interlocking the tassel material with the loop, substantially as described.
17. In a machine of the class described, the combination with a collar for receiving and holding a heading loop, of means for pulling tassel material through said loop; cooperating jaws for holding the tassel material in said loop; 25 cooperating fingers for combing the tassel material into folded position on said loop; and means for binding the folded portions of the tassel material to produce a tassel on said loop, substantially as described.
18. In combination, a collar constituting means for holding a heading loop thereon and for receiving tassel material therethrough; and cooperating fingers arranged 35 to comb the tassel material into folded position upon said loop, said collar having an opening therein to permit the tassel material to be received on said loop, substantially as described.
19. In combination, a collar constituting means for holding a heading loop thereon and for receiving tassel material therethrough; a reciprocating shaft; and pivoted fingers carried by said shaft and provided 45 with hooks adapted to engage and fold the tassel material upon said loop; said collar having an opening therein to permit the tassel material to be received on said loop; the said hooks jointly comprising means for 50 combing said tassel material, substantially as described.
20. In combination, a collar constituting means for holding a heading loop thereon and for receiving tassel material therethrough; a pivoted arm carrying said collar; a reciprocating shaft; pivoted fingers arranged on said shaft to open about said collar; hooks on said fingers adapted to engage and comb the tassel material into folded position over said loop; and means for pivoting said arm and reciprocating said shaft, substantially as described.
21. In combination, a collar constituting means for holding a heading loop thereon and for receiving tassel material there- 65
- through; a pivoted arm carrying said collar; pivoted jaws on said arm for holding the tassel material; means for operating said jaws; and means for interlocking the tassel material with said loop, arranged to be operated while the tassel material is held by said jaws, substantially as described. 70
22. In combination, a collar constituting means for holding a heading loop thereon and for receiving tassel material therethrough; cooperating fingers arranged to comb the tassel material into folded position upon said loop; means for compressing the folded material to receive a binder; and means for binding the folded material; said 75 collar having an opening therein to permit the tassel material to be received on said loop, substantially as described.
23. In a machine of the class described, the combination with a pivoted arm, of a 80 collar held thereby and constituting means for holding a heading loop thereon and for receiving tassel material therethrough; pivoted jaws on said arm having extremities arranged to seize tassel material protruding through said collar; and means for opening and closing said jaws, substantially as described.
24. In a machine of the class described, the combination with a pivoted arm, of a 85 collar held thereby and constituting means for holding a heading loop thereon and for receiving tassel material therethrough; jaws pivoted on said arm and having extremities arranged to seize tassel material protruding through said collar; spring means acting on said jaws to urge them in open position; and means arranged to engage said jaws and close them against the tension of the spring means, substantially as described. 90
25. In a machine of the class described, the combination with a pivoted arm, of a 95 collar held thereby and constituting means for holding a heading loop thereon and for receiving tassel material therethrough; a pair of spring opened cooperating jaws pivoted to said arm and having extremities arranged to seize tassel material protruded through said collar; a main operating mechanism; means under the control of said 100 mechanism for pivoting said arm; and means under the control of said mechanism for engaging and closing said jaws upon the pivoting of said arm, substantially as described. 105
26. In a machine of the class described, the combination with a collar for holding fringe heading thereon and means for feeding the tassel material to be applied to said heading, of an arm supporting said collar and pivoted to swing the same into line to receive the tassel material therethrough; a pair of jaws associated with the arm and collar to seize the received tassel material; and means for shearing off the tassel ma- 110
- 120
- 125
- 130

terial between the collar and feeding means after the tassel material has been seized by said jaws, substantially as described.

27. In a machine of the class described, 5 the combination with a collar for holding fringe heading thereon and for receiving tassel material to be applied to said heading, of a pivoted support for said collar; a main operating mechanism and means controlled 10 thereby for pivoting said support; a pair of pivoted jaws associated with said support and collar; and means under the control of the operating mechanism to actuate said jaws and cause the same to seize and hold 15 the tassel material received by said collar, substantially as described.

28. In combination with a collar adapted 20 to hold fringe heading thereon and to receive tassel material to be applied to said heading, of a pair of holding jaws arranged to close on the tassel material received by 25 said collar; a main operating mechanism; and means under the control of said operating mechanism for automatically closing said jaws, substantially as described.

29. In combination with a collar adapted 30 to hold fringe heading thereon and to receive tassel material to be applied to said heading, of a pair of holding jaws arranged to close on the tassel material received by 35 said collar; a pair of folding fingers arranged to comb the tassel material into folded position on the fringe heading; a main operating mechanism; means under the control of said operating mechanism for closing 40 said jaws; and means under the control of said mechanism for actuating said folding fingers subsequently to the closing of said 45 jaws, substantially as described.

30. In combination with a collar adapted 50 to hold fringe heading thereon and to receive tassel material to be applied to the said heading, of a pair of holding jaws arranged to close on the tassel material received by 55 said collar; a pair of folding fingers arranged to comb the tassel material into folded position on the fringe heading; a main operating mechanism; means under the control of said operating mechanism for closing 60 said jaws; means under the control of said mechanism for actuating said folding fingers subsequently to the closing of said 65 jaws; and instrumentality under the control of said mechanism for binding the folded tassel material at the conclusion of the folding operation, substantially as described.

31. In combination with a collar adapted 65 to hold fringe heading thereon and to receive tassel material to be applied to said heading, of a pair of holding jaws arranged to close on the tassel material received by 70 said collar; a pair of folding fingers arranged to comb the tassel material into fold-

ed position on the fringe heading; a main 65 operating mechanism; means under the control of said operating mechanism for closing said jaws; means under the control of said mechanism for actuating said folding fingers subsequently to the closing of said jaws; 70 instrumentality under the control of said mechanism for binding the folded tassel material at the conclusion of the folding operation; and trimmers for trimming the ends of the bound tassel material controlled by 75 said mechanism, substantially as described.

32. In combination, a collar adapted to hold fringe heading thereon and to receive tassel material to be applied to said heading; a pair of jaws arranged to seize and hold 80 the tassel material when received by the collar; a pair of fingers for folding the tassel material upon the heading; a binding device arranged to operate to bind the folded tassel material; cooperating trimmers 85 arranged to trim the bound tassel material; a main operating mechanism comprising a cam shaft; and means controlled by the cams of the cam shaft controlling the operation of the seizing and holding jaws, the 90 folding fingers, the binding device and the trimmers, all in timed relation, substantially as described.

33. In combination with a collar adapted 95 to hold fringe heading thereon and to receive tassel material to be applied to said heading, of a reciprocating rod provided with spring claws adapted to pull the tassel material through said collar and the fringe heading thereon; and means for effecting 100 the opening and closing of said jaws, substantially as described.

34. In combination with a collar adapted 105 to hold fringe heading thereon and to receive tassel material to be applied to said heading, of a reciprocating rod provided with spring claws adapted to pull the tassel material through said collar and the fringe heading thereon; and a sleeve movably mounted on said rod for effecting the opening 110 and closing of said claws, substantially as described.

35. In a machine of the class described, the combination with a collar for holding fringe heading thereon and means for feeding tassel material to be applied to said heading, of an arm supporting said collar and pivoted to swing the same into line to receive the tassel material; a reciprocating rod in line with the feeding means to pass through said collar when the latter is in receiving position; claws on said rod adapted to seize the tassel material and pull the same through said collar; and means combined with said rod for effecting the opening and closing of said claws, substantially as described.

36. In combination with a collar adapted

- to hold fringe heading thereon and to receive tassel material to be applied to said heading, of a reciprocating rod provided with spring claws arranged to seize the tassel material and to pull the same through said collar and the fringe heading thereon; a sleeve having independent movement on the rod and arranged to lock said claws on the seized tassel material; means for reciprocating said rod; and means for actuating said sleeve, substantially as described. 37. In combination with a collar adapted to hold fringe heading thereon and to receive tassel material to be applied to said heading, of a reciprocating rod provided with claws arranged to seize the tassel material and to pull the same through said collar and the fringe heading thereon; a sleeve having independent movement on the rod and arranged to cooperate with the claws thereof to lock the claws on the seized tassel material at one side of the collar and to unlock the claws for the release of the tassel material at the opposite side of the collar, substantially as described. 38. In combination, a collar; a rod arranged to be reciprocated through said collar; claws arranged on said rod; a sleeve mounted for independent movement on the rod and adapted to engage and lock said claws; means for reciprocating said rod; and means for moving said sleeve in relation to the reciprocation of said rod to provide for keeping said claws locked during the passing thereof through said collar, substantially as described. 39. In combination, a collar; a rod arranged to be reciprocated through said collar; claws on the rod arranged to be carried through said collar; a sleeve mounted for independent movement on the rod adapted to engage and lock said claws; a main operating mechanism comprising a cam shaft; means under the control of said mechanism for positioning the collar to receive said rod and other means controlled by the cams of the cam shaft to operate said rod and said sleeve in relation to effect the unlocking of said claws before they are passed through said collar in one direction and then the locking of said claws before they pass through said collar in the opposite direction, substantially as described. 40. In combination; a rod arranged to be reciprocated; a collar; an arm supporting the collar and movable to position the same to receive said rod; claws on the rod arranged to be carried through said collar; a sleeve mounted for independent movement on the rod and adapted to engage and lock said claws; a main operating mechanism; and means under the control of said mechanism for first pivoting said arm to position said collar to receive said rod and then to operate said rod and said sleeve to effect the locking of said claws before they are passed through said collar, substantially as described. 41. In combination with a reciprocating rod and a reciprocating sleeve, of claws on said rod arranged to be engaged and locked by said sleeve; of means for relatively operating said rod and sleeve to provide first for the advance of said rod to unlock said claws and then for the advance of said sleeve to lock said claws, substantially as described. 42. In a machine of the class described, the combination with a collar for holding fringe heading thereon and for receiving therethrough tassel material to be applied to said heading, of means for combing the tassel material into folded position upon the fringe heading comprising a pair of fingers pivoted for closing movement and having means for engaging the tassel material at opposite ends of the collar; and a movable mounting for withdrawing said fingers during the closing movement thereof, substantially as described. 43. In a machine of the class described, the combination with a collar for holding fringe heading thereon and for receiving tassel material to be applied to said heading, of a pair of fingers having hooked ends adapted jointly to comprise means for combing the tassel material into folded position upon the fringe heading; a reciprocating shaft; and means on said shaft pivotally supporting said fingers for opening and closing movement, substantially as described. 44. In a machine of the class described, the combination with a collar, of a reciprocating shaft; a pair of fingers pivotally supported upon said shaft for opening and closing movement and adapted to receive tassel material from said collar; and means associated with said fingers to cause them to open for passing at opposite sides of the collar, into position to receive the tassel material when the shaft is moved in one direction and to cause them to comb said tassel material on the retiring movement thereof, substantially as described. 45. In a machine of the class described, the combination with a collar, of a reciprocating shaft in line with said collar; a pair of fingers having pivoted support on said shaft for opening and closing movement; and means associated with said fingers for causing them to open on the advancing movement of said shaft and to close on the retiring movement thereof, substantially as described. 46. In a machine of the class described, the combination with a collar for holding fringe heading thereon and for receiving tassel material to be applied to said head,

- ing, of a reciprocating shaft in line with said collar; a pair of fingers having pivoted support on said shaft for opening and closing movement; means associated with said fingers for causing them to open on the advancing movement of said shaft and to close on the retiring movement thereof; and hooked members on said fingers jointly comprising means for engaging and combing 10 the tassel material into folded position upon the heading fringe under the closing movement of the fingers, substantially as described.
47. The combination of a movable shaft; 15 a pair of fingers having pivoted support intermediate their ends upon said shaft; a pull spring connecting corresponding ends of the fingers whereby normally to open them; and means on the shaft arranged to 20 engage and effect the closing of the fingers against the tension of the spring upon the movement of the shaft, substantially as described.
48. In a machine of the class described, 25 the combination with a collar for holding a heading loop therearound and for receiving tassel material therethrough to be applied to said loop, said collar having an opening at one side, of a reciprocating 30 shaft; a pair of fingers having pivoted support upon said shaft for opening and closing movement; means for causing said fingers to open to be positioned about said collar on the advancing movement of said 35 shaft; hooks on said fingers; and means for closing said fingers on the retiring movement of the shaft to cause said hooks jointly to comprise means for combing said tassel material into folded position through the 40 side opening in said collar and upon the loop held thereby, substantially as described.
49. In a machine of the class described, 45 the combination with a collar for holding fringe heading thereon and for receiving tassel material to be applied to said heading, of a pair of fingers having hooked ends adapted jointly to comprise means for combing the tassel material into folded position upon the fringe heading; a reciprocating 50 shaft; means on said shaft pivotally supporting said fingers for opening and closing movement; means for causing said fingers to open and close to effect the combing operation; a pivoted arm supporting said collar, a 55 main operating mechanism; and means under the control of said mechanism for pivoting said arm and reciprocating said shaft in timed relation, substantially as described.
50. In a machine of the class described, 60 the combination with means for feeding a wire, of a wire severing device; a swingable anvil; a die member arranged to cooperate with the anvil to form the severed wire into a binding staple; and means arranged to be 65 operated by the die member to cause the anvil to swing clear of the die member to permit of the application of the binding staple thereby, substantially as described.
51. In a machine of the class described, 70 the combination with a wire cutting device comprising a bifurcated bar arranged for reciprocation, of a pivoted anvil normally positioned opposite the furcations of said bar; a second bar arranged for reciprocation and having a die slidable between said furcations 75 to cooperate with said anvil in forming a wire staple; and means for swinging the anvil clear of the die to permit of the application of the binding staple thereby, substantially as described.
52. In a machine of the class described, 80 the combination with a wire cutting device comprising a bifurcated bar arranged for reciprocation, of a pivoted anvil normally positioned opposite the furcations of said bar; a second bar arranged for reciprocation and having a die slidable between said furcations 85 to cooperate with said anvil in forming a wire staple; means arranged to be operated by the second bar to cause the anvil to swing clear of the die member to permit of the application of the binding staple thereby; a rock shaft; and means on the rock shaft for operating each of said bars, substantially as described.
53. The combination in a machine of the 90 class described, of a pair of die members arranged to cooperate in wire binding a tassel; and a pair of compressor fingers arranged to be closed upon the tassel to hold the same compressed to size for the binding operation; and means on one of the die members arranged to act on the fingers for operating the same prior to the binding operation, substantially as described.
54. The combination, in a machine of the 95 class described, of means for forming a wire staple including a movable die member arranged to advance the formed staple about a tassel to be bound; a pair of compressor fingers arranged to compress the tassel to size to receive the staple thereon; means for closing the free arms of the staple upon the tassel whereby to bind the same; and means for trimming the bound tassel, substantially 100 as described.
55. A machine of the class described including a main frame; a main operating shaft; an arm rest arranged on the frame and having a slot; a collar movable in said slot and projecting above the rest to receive a heading loop thereon and means arranged to be operated by said shaft for moving said collar.
56. A machine of the class described including a main frame; a main operating shaft; an arm rest arranged on the frame and having a slot; a feed tube for tassel material in line with said slot; a collar movable in said slot; mechanism arranged to be op- 110 115 120 125 130

erated by the shaft for moving the collar into position to receive tassel material from said tube; a claw device for carrying the tassel material through said collar; a sleeve co-acting with the claw device to lock the same upon the tassel material; mechanism actuatable by the shaft for operating the claw device; and mechanism actuatable by the shaft for operating the sleeve, substantially as described.

57. A machine of the class described including a main frame; a main operating shaft; an arm rest arranged on the frame and having a slot; a feed tube for tassel material in line with said slot; mechanism arranged to be operated by said shaft for moving the collar into position to receive

tassel material from said tube; a claw device for carrying the tassel material through said collar; a sleeve co-acting with the claw device to lock the same upon the tassel material; mechanism actuatable by the shaft for operating the claw device; mechanism actuatable by the shaft for operating the sleeve; a pair of spring opened jaws arranged under the rest; and mechanism actuatable by the shaft for forcibly closing said jaws upon the tassel material drawn through said collar by said claw device, substantially as described.

In testimony whereof I have signed my name to this specification.

ROBERT E. WALLISER.
